[57] CLAIM

The ornamental design for a mirror for automobile visor, as shown and described.

DESCRIPTION

FIG. 1 is a perspective view of a mirror for automobile visor showing my new design, it being understood that the broken lines are for illustrative purposes only.

FIG. 2 is a bottom plan view thereof;

FIG. 3 is a side elevational view thereof, the opposite side being a mirror image of that shown;

FIG. 4 is a rear elevational view thereof;

FIG. 5 is a top plan view thereof;

FIG. 6 is a front perspective view thereof showing a pair of mounting clips therefor in exploded condition; and

FIG. 7 is a rear perspective view thereof showing the mounting clips in position.

The mounting clips have been omitted in FIGS. 1 thru 5 for convenience of illustration.
